UNITED STATES PATENT OFFICE

JOHN STUART FLEMING, OF TORONTO, ONTARIO, CANADA, ASSIGNOR, BY MESNE ASSIGNMENTS, TO NIAGARA FOLD, INC., OF NIAGARA FALLS, NEW YORK, A CORPORATION OF NEW YORK

MANIFOLDING DEVICE

Application filed May 18, 1927. Serial No. 192,246.

This invention relates to equipment adapted for use in effecting manifold inscription, whether by autographic writing or by a writing machine, such as a typewriter, and with respect to its more specific features, to the transfer material equipment.

One of the objects of the invention is the provision of a practical packet or block of transfer sheets in which superposed transfer sheets are at all times and in all positions of the packet firmly attached together in superposed relation, so as to be readily shifted as one, the transfer sheets at all times being held in spread-out condition and adapted 10 freely to receive therebetween the record strips on which the records are to be made by manifolding, the transfer sheets being restrained from bodily movement in their own planes relative to each other, however the 15 packet may be shifted and during the intervals between the making of records at different shifted positions on the record strips, the packet at all times being adapted for freely being shifted from one writing position to 20 another, or for having the record strips shifted relative thereto.

Another object of the invention is the provision of a device for facilitating multiplicity of manifolding operations which may or 25 may not require the use of a platen.

Other objects of the invention will in part be obvious and will in part appear herein-after.

The invention accordingly comprises the 30 features of construction, combinations of elements, and arrangement of parts, which will be exemplified in the construction herein-after set forth and the scope of the application of which will be indicated in the claims.

For a fuller understanding of the nature and object of the invention, reference should be had to the following detailed description taken in connection with the accompanying drawings, in which:

Fig. 1 is a perspective view of a packet embodying certain features of the invention.

Fig. 2 is a view similar to Fig. 1, showing record strips in manifolding relation.

Fig. 3 is a view similar to Fig. 2, but up- 45 side down, and slightly modified.

Fig. 4 is a perspective view of a packet, illustrating further modification.

Figs. 5 and 6 conventionally illustrate the invention as applied to a typewriting machine in one way, and

Fig. 7 illustrates typewriter application 55 slightly modified.

Fig. 8 is a perspective view of a modified form of zigzag pad of record strip with which the transfer packet may be employed, 60 and

Fig. 9 is a perspective view showing the transfer packet associated with the form of zigzag pad illustrated in Fig. 8.

Referring now more specifically to the drawings, and more particularly to Figs. 1 and 2 thereof, the numerals 1 each indicate a separate transfer sheet as, for instance, the "carbon" or carbon sheet, in use for transferring inscription from one record strip to another record strip, in a manifolding manner. The coating of transfer material on the sheets 1 is on the under surface of each of said sheets, so that the body paper, of which these sheets are usually composed is 75 exposed in their upper surfaces. The several transfer sheets 1 are supported in superposed relation to each other and to a flat supporting member such as the platen 2, which platen is also adapted to serve as a shoe, and the 80 said platen and the set of transfer sheets are attached and firmly held together so as to be transportable, manipulable, and shiftable, as one.

As illustrated in Figs. 1 and 2, the transfer sheets 1 are attached together at each of two of their opposite sides by lines of stitching 3 and 4. Between these lines of stitching the transfer sheets are unattached to each other and are adapted to permit the paper 90 record strips 5 (Fig. 2) on which the inscription is to be made, freely to pass between the transfer sheets. One of the record strips which is to receive the original inscription will lie above the uppermost transfer sheet 95 1 and is indicated at 6. To admit of clearer illustration, said uppermost transfer sheet is broken off.

For the purpose of assisting in retaining the original record strip 6 in close relation 100

to the uppermost transfer sheet, the assemblage, or packet, of transfer sheets 1 is provided with a retainer guide or strip 7, the original record strip 6 passing between the 5 retainer strip 7 and the uppermost transfer sheet 1. If desired, an additional retainer strip similar to the strip 7, may be provided at the opposite end of the packet. Other guide strips may be provided below in order 10 to support sheets 5 passing through, and giving the further advantage of separating the sheets 5.

By the arrangement described there is provided a packet, or block, of firmly attached, 15 relatively superposed, transfer sheets, which is always in condition to have the record strips interleaved with the transfer sheets in manifolding relation, and which may be shifted back and forth upon long continuous 20 record strips, and to any position in which it is desired to make a manifold inscription, whether autographically or by machine, such as a typewriter, the platen or supporting shoe 2 always shifting with the transfer 25 sheets and always being in operative position.

In the form illustrated in Figs. 1 and 2, the element 2 serves not only as a platen, but also as a protective shoe for the under face of the packet, and especially for the lower- 30 most transfer sheet 1, being adapted to protect the bottom of the packet against surface marring, abrasion, tearing, rumpling, and the like, which might follow from sliding shifting of the packet on the supporting sur- 35 face on which it rests. It will be observed that the element 2 also serves as a support or a supporting shoe for the assembly of transfer sheets sustaining them in smooth extended position at all times in such a manner as 40 to promote correct functioning of the assembly and to insure the best possible transfer inscription.

In Fig. 3 a slightly modified form of packet is illustrated, the view in this instance 45 being upside-down so as to disclose the bottom face of the packet. It will be seen that the arrangement in Fig. 3 is similar to that in Figs 1 and 2, except that the bottom supporting shoe 8 corresponding in position and 50 function to the shoe 2, is in the form of a supporting frame having a central opening exposing the underlying record strip 5. The frame 8 also provides a shoe along with which the packet may be shifted without abrasion 55 of the transfer sheets. The aperture or opening 9 in the frame 8, exposes the lowermost record strip, or in its absence, the lowermost transfer sheet. Hence, under proper conditions, this packet of transfer sheets may be 60 used along with other and separate transfer sheets, if desired. It will be understood that the illustration in the drawings is largely di- agrammatic. The packet of Figs. 1, 2 and 3, including the supporting shoe or platen 2 or 65 the frame or shoe 8, is scarcely thicker than

the assemblage of transfer sheets. In Figs. 1, 2, and 3, the stitching 3 and 4 may be of wire or thread, and the transfer sheets lie one on top of another without intervening separators, although such separators may be used, 70 as will hereinafter appear.

In Fig. 4 a still further modification of the transfer sheet packet is illustrated, the construction therein disclosed including special features of invention adapted to provide for a more extensive and practical use of the transfer packet. In Fig. 4, the transfer sheets are attached in superposed relation to each other and to the platen or shoe 2 through 75 the instrumentality of transfer sheet retainer strips 10, 11, 12, and 13, at the opposite sides 80 of the transfer sheets.

In the embodiment illustrated, the retainer strips 10, 11, 12 and 13 are similar and consist of thin strips extending longitudinally 85 of the platen 2, these strips being sufficiently wide so that uncoated marginal areas of the transfer sheets 1 may overlap the retainer strips and be attached to the under surfaces 90 of the retainer strips by spots or lines of paste or other suitable adhesive, as indicated at 14 and 15. Outside the pasted edge of the lowermost transfer sheet the lowermost retainer strip 11 is pasted to the upper face 95 of the platen 2 by a line of paste indicated at 16. The next superposed transfer sheet 1 is pasted to the retainer strip 10, but in this instance it is preferred to paste the outer margin of the strip 10 to the upper face of the strip 11, as indicated at 17. It will be 100 understood that the retainer strips 12 and 13, at the opposite side, are similarly pasted to each other, to the transfer sheets 1, and to the platen 2, as just explained in connection 105 with the strips 10 and 11. Also it will be 110 understood that any desired number of transfer sheets may thus be attached together and to the platen 2. As in the embodiment illustrated in Figs. 1 and 2, record strip retainer guides 18 may be employed, corresponding 115 to the retainer guides or strips 7. The guides 18 may consist of strips pasted to the upper faces of the sheet retainer strips 10 and 12, as illustrated in Fig. 4. Like the 120 packet of Figs. 1, 2 and 3, the record strips 5 are adapted freely to pass between the transfer sheets 1 of the construction illustrated in Fig. 4, and the original record strips 6 will be engaged under the retainer guides 18. Besides serving to attach the transfer sheets 125 together and to the platen or shoe 2, the retainer strips 11 serve to space the adjacent superposed transfer sheets 1 from each other at their margins, rendering it easier to string or thread the record strips in the intervals 130 between the adjacent transfer sheets. It will be noted that in each of the constructions illustrated, the front and rear edges of the superposed transfer sheets are unattached to each other except at their side margins, so

that they are readily separable for the introduction of the record strips.

By the construction described, the record strips 5 may readily be inserted between the transfer sheets at one edge of the packet and emerge or be drawn out at the opposite edge and thereafter the packet, assemblage, or set of superposed transfer sheets may be shifted at will along the record strips into any desired position for inscription, this shift movement being possible in either of opposite directions, the arrangement readily providing for shift movement of the transfer sheets while the record strips are stationary, or vice versa, or both the transfer sheets and the record strips may be shifted simultaneously. It will be seen that the set of attached transfer sheets are strung on the record strips so as selectively either to be shifted relative to the record strips, or to have the record strips shifted relative thereto.

In each of the embodiments illustrated all the parts may be made of relatively thin strips or sheets of paper, although other materials, such as metal, wood, celluloid, and the like, may be used. The platen 2 may consist of a sheet of paper as, for instance, card-board or kraft paper; which is relatively thick as compared with the record strips and has some resilience. The retainer strips, 10, 11, 12 and 13 may also be composed of card-board or kraft paper. Under certain conditions of use the paper platen or shoe promotes manipulation of the packet and the operation of manifolding to better effect than were it made of some other material as, for instance, a hard material like celluloid, wood, or metal. But it is to be understood that the platen or shoe 2 may be composed of such other materials under conditions wherein advantage might be gained.

In the embodiments illustrated the platen or shoe 2 is of rectangular shape and provides a support to which the several transfer sheets are attached in superposed relation to each other and for being held in operative position to the record strips and while being shifted from one to another writing position. This supporting shoe extends across and at each of the opposite sides 19, 20, 21 and 22 of the centre 23, of the main body, or writing area, of the transfer sheets 1, and the attachment of the sheets to the supporting shoe as, for instance, in the manner before explained, serves to hold the writing area of the transfer sheets in generally flat, spread-out condition at all positions and during shifting of the packet, thus in a measure tensioning the transfer sheets. The underlying paper record strips 5 being, as it were, strung on the packet between the separate transfer sheets, are maintained in operatively close relation to the record strips, although sliding movement relative thereto is permitted. The record strip retainers 7 or 18 are thus

shiftable with the platen or shoe 2 and cooperate to guide and retain the uppermost record strip in operative manifolding position. The record strips may be supplied from one or more rolls, or from the zigzag folded pad of long continuous strip, diagrammatically shown in Fig. 4 at 25. Each of the record strips is provided with a series of similar printed forms 26 adapted to register with each other, so that inscription made upon an outermost printed form may be manifolded in the same relation on the underlying printed forms of the other record strips. The manifolding packet of superposed attached transfer sheets above referred to may be supported alongside the packet of record strips and, having been strung on the record strips in the manner before explained, may be shifted into operative manifolding inscribing relation, with succeeding forms, or the record strips may be advanced relative to the packet. Having inscribed one set of printed forms, and shifted the packet to the succeeding set, the inscribed set may be torn off along the weakening lines 27 which are provided therefor. The paper platen affords a sufficiently resistant surface for cooperating to obtain manifold inscription and also is relatively soft, as is usually preferred when inscription is made autographically, as would be the case under these conditions. The width of the transfer sheet packet need only be such as to permit passage of the record strips with sufficient play to permit easy shifting. When all the frame parts of the packet are composed of light weight material such as paper, a convenient device is thereby provided for manifolding a large number of records in one writing and one which may be readily transported, and is relatively inexpensive.

Instead of providing for shifting the transfer sheet packet on the record strips by hand, the record strips may be shifted relative to the packet by a strip-shifting member as, for instance, by the rotary platen of a typewriting machine. Fig. 5 conventionally illustrates the platen portion common to many well-known forms of typewriting machines. The frame of the typewriting machine is indicated at 30. The numeral 31 indicates the platen carriage which reciprocally shifts in letter-spacing direction. Mounted on the carriage 31 is the rotatable generally cylindrical platen 32, which is adapted to serve as a record strip-feeding or record strip-shifting member. The record strips are indicated by the numerals 5 and 6, as in the other figures of the drawing. The rotary platen 32 is supported on a vertically movable shift frame 33 for accommodating it for different case-lettering, as small letters and capitals. The printing type bar of the typewriter is indicated at 34. Shiftable up and down with the platen 32 is a transfer sheet 130

packet generally similar to that illustrated in Fig. 4, this packet being indicated in Fig. 5 by the numeral 35, the numeral 36 indicating the outermost transfer sheet, corresponding to the outermost of the transfer sheets 1 of Fig. 4. Underlying the transfer sheet 36 are other similar transfer sheets, being in the same relation as in Fig. 4, these transfer sheets being attached together and to a plate 37, which plate may correspond to the supporting shoe or platen 2 of the other figures, and may serve as a platen auxiliary to the main or rotatable platen 32 of the typewriter. For supporting the packet 35 in front of the rotatable platen 32, the auxiliary platen or supporting shoe 37 is provided with laterally extending ears 38 at each of its opposite sides, and these ears are received between two sets of gripper jaws 39 and 40, removably attached to the frame 33, and shiftable up and down with said frame, being also adjustably attached to said frame, as indicated at 41. The auxiliary platen 37 is adjustable in line-spacing direction relative to the printing point, so that it may be shifted and different areas of the transfer sheets be placed in the printing line, thus rendering it possible to progressively utilize the full area of the transfer sheets. Like the other modifications, the packet 35 may be provided with a retainer 42 for the outermost record strip 3. For the purpose of retaining the packet 35 in its different adjusted positions, the ears 38 may be provided with dogs 43 which engage teeth 44 in the jaws 39 which coact to retain the supporting shoe or auxiliary platen. In the form illustrated in Fig. 5 the auxiliary platen is slightly curved to conform to the surface of the main platen 32, as shown clearly in Fig. 6, although it is to be understood that a flat auxiliary platen may be employed, as shown at 45, in Fig. 7. The auxiliary platen may readily be removed from operative position by being detached from the holding jaws 39 and 40.

In its association with the rotary platen of the typewriter, the supporting member or shoe for supporting the transfer sheets may be of the type illustrated in Fig. 8, in which the bottom transfer sheet is exposed through the aperture 9. In Fig. 7 the element 45 is a platen, but the broken line 50 indicates the position of the edge of the aperture 9, in case the apertured frame be substituted for the platen 37. By using the apertured frame alongside the rotary platen 32, it will be seen that the rotary platen may have the usual complement of record strips and interleaved transfer strips, and that printing impression on the packet is manifolded also by the other transfer strips, which latter are separate and in addition to those of the packet. When this apertured supporting shoe or frame is made of paper, the flexibility of the frame promotes effecting contact between the

bottom transfer sheet of the packet and the outer record strip between the frame and the rotary platen 32. When the imperforate shoe or platen is made of paper, the flexibility of the paper promotes its close contact with the rotary platen at the time of impression so that the auxiliary platen is supported by the rotary platen against the blow of the type, efficient printing being thus assured.

Referring to the association of main or rotary platen 32, and an auxiliary platen, it is noted that the arrangement described provides for selective use of either of the auxiliary platens 37 or 45. By rotating the platen 32 the record strips will be shifted or fed in line-spacing direction, but it will be observed that the transfer sheets carried by the auxiliary platen do not extend between the platen 32 and its cooperative presser feed roll 46. Thus the thickness of the assemblage of strips at the line of feed is less than were the transfer strips included therebetween, and hence the tendency of the record strips to be displaced relative to each other by the feed mechanism and thereby move superposed printed forms out of registry, is decreased.

The invention referred to herein is adapted to promote the facility with which records may be made by a typewriting machine having a rotary strip-shifting member, or roller, such as the platen 32. The rotary platen of the typewriting machine may be utilized in the ordinary manner, to feed interleaved record strips and transfer strips as, for instance, in making records on successive independent letterheads or sheets. When it is desired to utilize long continuous record strips in the typewriting machine, the auxiliary platen with its attached transfer sheets may be applied to the typewriting machine and held by the jaws 39 and 40, the record strips continuing to be fed by the rotary platen 32. When adapted for use with mechanical feed of the record strips, as in a typewriter, the relation between the adjacent transfer sheets of the packet should be loose, which may be obtained by using a suitable thickness for the retainer strips which span the margins of the transfer sheets. Promotion of feed by the usual feed devices of the typewriter is enhanced by employing a flat auxiliary platen instead of the curved platen shown in Figs. 5 and 6. But either type of auxiliary platen may be used.

It will be understood that the illustration in Fig. 7 diagrammatically represents the platen of a typewriter associated with a detachable transfer sheet packet of the construction shown in detail in Fig. 4. In Fig. 7, the platen 45, is similar to the platen 2 of Fig. 4, but will be provided with additional features adapting it for attachment to the frame 33 of the typewriter shown in Fig. 5. As the means of attachment to the typewriter

may be the same as illustrated in Fig. 5, reference is made to the latter figure in illustration of the attaching device.

In the modified pad illustrated in Figs. 8 and 9, the record strips are superposed relative to each other and zigzag folded as in Fig. 4. But at one end of this supply pad the different folds of the strip 50, which is the bottom of the manifold copies, are hinged together so as to provide folded leaves working one on another much like the leaves of a book. To effect this hinging one end face 51 of the packet is brushed over with paste, the superposed turns of the strip 50 being thus joined by an area of paste or other suitable adhesive 52 so as to hinge the turns together. At the side 53 adjacent the face 51 the leaves of all the strips are bonded together by an area of paste 54, which retains the leaves together and restrains them against lateral movement relative to each other. The attachment of the leaves at the area 54 is such that it may readily be broken so as to permit the strips to unfold and to be moved relative to each other. When the frame 8 having the opening 9 is employed with the zigzag pad of Fig. 8, the open frame 8 will lie on or above the record strip 50, as illustrated in Fig. 9; whereas the other record strips of the zigzag pad will be above the frame 8 with the transfer strips in such relation as to transfer inscription from the original strip 55 to the duplicate strip 56 and, through the opening 9, to the strip 50, which latter is the one having its folded leaves hinged together at 52. As the frame 8 is shifted along between the record strips the advance edge 57 of the frame 8 and the advance edge 58 of the frame guides or strips 59 act as tools to break the bonds at 54, thereby disconnecting the so bonded strips from each other at the area 54, leaving the two upper strips free for manipulation. But the hinging at 52 will not be broken. Should paste at area 52 penetrate sufficiently to cause the strips 55 and 56 to adhere to the strip 50, it will be also broken and the different strips disconnected by the advance edges of the frame 8 and the frame guides 59. In order that the more delicate transfer sheets 60, which are shiftable with the frame, may not be injured, their edges 61 are in rear of the edges 57 and 58. When used with the bonded strips of Fig. 8, the frame 8 and the guides 59 should be relatively stiff so as to provide for parting the strips where they are bonded.

Thus by the above described construction are accomplished, among others, the objects hereinbefore referred to.

Since certain changes may be made in the above construction, and different embodiments of the invention could be made without departing from the scope thereof, it is intended that all matter contained in the above

description or shown in the accompanying drawing, shall be interpreted as illustrative and not in a limiting sense.

It is also to be understood that the following claims are intended to cover all of the generic and specific features of the invention and also to cover all intermediate variations of the scope thereof.

Having described my invention, what I claim as new and desire to secure by Letters Patent is:

1. A manifolding device including, in combination, a supporting shoe, a plurality of transfer sheets in superposed relation to each other and to said supporting shoe, a plurality of transfer sheet-retainer strips in superposed relation to each other, pasted to each other and to said supporting shoe, said sheet-retainer strips being pasted to uncoated areas of said transfer sheets, respectively, and one or more strip-retainer strips carried by and shiftable with said supporting shoe.

2. A manifolding device, including, in combination, a strip-shifting member, of generally cylindrical shape, a platen and a transfer sheet, said platen and transfer sheet being attached together in superposed relation to each other and adapted to receive therebetween a record strip adapted to be shifted by said member, and means adapted to retain said platen stationary as said member is shifted.

3. A manifolding device including, in combination, a strip-shifting member, a transfer sheet, an auxiliary platen removable from operative position, said member disposed and adapted selectively to serve as a platen in the place of said auxiliary platen, said auxiliary platen and transfer sheet being attached together in superposed relation to each other and adapted to receive therebetween a record strip adapted to be shifted by said member, and means adapted to retain said platen stationary as said member is shifted.

4. A manifolding device including, in combination, a plurality of transfer sheets in superposed relation to each other, and a supporting shoe to which said sheets are attached for being held in operative position to record strips passing between said sheets, said supporting shoe extending across and at each of the opposite sides of the writing area of said sheets, and adapted to hold said writing area in generally flat spread-out condition, the attaching means between said supporting shoe and sheets including retainer strips to which said sheets are pasted respectively, said retainer strips being pasted to each other.

5. A manifolding device including, in combination, a rotatable platen, a transfer-sheet supporting shoe, relatively superposed transfer sheets attached to and held in spread out condition by said supporting shoe, a shift

frame on which said platen is mounted and gripper jaws carried by said shift frame, said sheet-supporting shoe movably engaging said gripper jaws for adjustment longitudinally of the rotative movement of said platen and supporting said sheets at the printing point relative to said rotatable platen.

6. A manifolding device including, in combination, a plurality of transfer sheets in superposed relation to each other, a record strip retainer positioned to expose the writing area of the outermost of said transfer sheets and to guide an original record strip 10 into contact with said outermost transfer sheet, said retainer being positioned on later mentioned shoe to form therewith a passageway for shift movement therein of said original record strip, and a shoe to which 15 said transfer sheets are attached at two opposite sides of the active transfer areas of said transfer sheets so as to hold said sheets in spread-out condition and provide intervals between said sides for passage of record 20 strips, said retainer being attached to said shoe.

7. A manifolding device including, in combination, a plurality of transfer sheets in superposed relation to each other, a record strip retainer positioned to expose the writing area of the outermost of said transfer sheets and to guide an original record strip into contact with said outermost transfer sheet, said retainer being positioned with reference to later mentioned platen to form therewith a passageway for shift movement therein of said original record strip, and a platen to which said transfer sheets are attached at two opposite sides of the active 30 transfer areas of said transfer sheets so as to hold said sheets in spread out condition and provide intervals between said sides for passage of record strips, said retainer being attached to said platen.

45 8. A manifolding device including, in combination, a plurality of transfer sheets in superposed relation to each other, a shoe to which said transfer sheets are attached so as to be held in spread-out condition and provide intervals between said sheets for passage of record strips, said transfer sheets being attached to said shoe at opposite sides of the active transfer area of said sheets so as 50 to hold said sheets in spread-out condition, said shoe having bond breakers positioned in advance of the free edges of said transfer sheets and so as to extend between adjacent record strips.

60 9. A manifolding device including, in combination, a supporting shoe, a plurality of transfer sheets in superposed relation to each other and attached to said supporting shoe so as to be held in spread-out condition 65 and a plurality of transfer sheet-retainer

strips in superposed relation to each other, pasted to each other and to said supporting shoe.

10. A manifolding device including, in combination, a supporting shoe, a plurality of transfer sheets in superposed relation to each other and attached to said supporting shoe so as to be held in spread-out condition and a plurality of transfer sheet-retainer strips in superposed relation to each other, pasted to each other and to said supporting shoe, said sheet-retainer strips being pasted to uncoated areas of said transfer sheets, respectively.

11. A manifolding device including, in combination, a supporting shoe of thin sheet material, a plurality of transfer sheets in superposed relation to each other and to said supporting shoe, attaching stitching passing through said supporting shoe, attaching the sheets and shoe together, said attaching stitching extending along two opposite edges of said transfer sheets and shoe and along opposite sides of the active transfer area of said sheets so as to hold the sheets in spread out condition, at least one continuous passageway being provided between adjacent transfer sheets between said opposite attaching stitching for the passage of a record strip, said supporting shoe and the attaching stitching between said sheets and shoe being flexible so as to permit bending of the manifolding device to conform to a curved longitudinal path.

In testimony whereof I affix my signature. 100
J. STUART FLEMING.
